DRINK DISPENSER

George C. Moreton, Winston-Salem, N.C., assignor to Electronic Data Controls Corporation, Winston-Salem,
N.C.

Filed Jan. 13, 1975, Ser. No. 540,325

Term of patent 14 years

Int. Cl. D15—08

U.S. CL. D15—112

FIG. 1 is a perspective view of the drink dispenser of my new design as viewed from the upper right front;

FIG. 2 is a perspective view as viewed from the upper left rear;

FIG. 3 is a front elevational view;

FIG. 4 is a right side elevational view; and

FIG. 5 is a bottom view.

I claim:

The ornamental design for a drink dispenser, as shown.
